TYPEWRITING MACHINE

Burnham C. Stickney, Elizabeth, N. J., assignor
to Underwood Elliott Fisher Company, New
York, N. Y., a Corporation of Delaware

Application May 27, 1927, Serial No. 194,591
Renewed April 24, 1931

6 Claims. (Cl. 197—82)

This invention relates to typewriting machines, and more specifically to a motor-driven repulser operative to forcibly restore an escapement-rocker after each typing impact and drive the universal bar against the type-bar to repulse or catapult the type-bar from the typing position of the platen and more quickly effect the letter-spacing release for the motor-driven carriage.

The Underwood carriage-feeding mechanism includes a type-bar actuated universal bar that vibrates an escapement-rocker carrying a holding dog and a stepping dog, the latter normally holding a tooth of an escapement-wheel, and the holding dog provided with a beveled face that holds said tooth during the stepping interval of the released stepping dog, as at the end of a key-stroke. The universal bar, having a direct connection to the escapement-rocker, operates the latter by a very short movement from the type-bars at the end of the key-stroke; hence the type-bars are projected by the key-levers to a point very close to the typing face of the platen before they pick up the universal bar to vibrate the rocker and effect a letter-space feed of the carriage. It is this quick, snappy vibration of the escapement-dogs before and after the type-impact that promotes speed in typing.

A type-bar usually is sluggish at the instant of type-impact, due to mechanical sacrifices made for acceleration of motion in front-strike typewriting machines, and no matter how fast the escapement-dogs may respond to release the carriage, if the type-bar is slow in leaving the platen after a type-impact, the speed of manipulation is retarded by the clashing of advancing type-bars.

The tooth of the escapement-wheel passes from the control of the stepping dog to the control of the beveled face of the holding dog, and the effect of the carriage-spring tension acting through the tooth of the escapement-wheel against the beveled face of the holding dog is to reverse the direction of reciprocation for the rocker at the end of the key-stroke, drive the universal bar to repulse the type-bar and accelerate the return movement of the rocker to release the escapement-tooth and permit the next advancing tooth of the escapement-wheel to engage the stepping dog for a letter-space movement. To effect this reaction of the beveled dog, the carriage-tension is necessarily high and this tension must be overcome by the operator at every carriage-return movement, but it is this combination of type-bar-actuated universal bar and beveled holding dog that gives the Under-

wood typewriting machine its reputation for speed in manipulation.

The beveled face of the holding dog in vibrating into contact with the edge of an escapement-wheel-tooth, serves as a stop for the forward movement of the rocker and is annoying to some operators who allow the fingers to linger upon the keys, besides being variable in its action under erratic manipulation of the keys. One feature of this invention includes the elimination of the beveled face and the substitution of a flat dog for holding the escapement-tooth at the end of a key-stroke, the movement of the rocker being limited in both directions of its movement by a pallet movable with the rocker and co-operating with a rotary driver that positively controls the throw of the rocker and the associated escapement-dogs regardless of the speed in manipulation of the keys.

One purpose of the present invention is to improve upon the highly developed carriage-feeding mechanism of the Underwood typewriter by retaining the speed-producing features, and further providing a motor-driven accelerator for the escapement-rocker, which becomes automatically operative at the end of the down stroke of the keys to speed up the "let-off" of the holding dog to more quickly release the carriage and simultaneously repulse and speed up the return of the type-bar after a type-impression; to provide an inactive power-driven driver rendered operable by the rocking of the key-actuated escapement-rocker in typing and rendered inoperative by the reverse or return movement of the rocker; to provide a power-driven toothed driver co-operative with a tooth-escaping pallet movable with the rocker and operative to first release a tooth of the driver at the end of a key-stroke, and in turn be driven by a tooth to rock and restore said rocker and universal bar to repulse the type-bar; to provide a driving element having a stored-up reserve power that is operative at all times to respond step by step to the key-actuated typing movement of the escapement-rocker and wholly restore the rocker and its connection to normal positions independently of the keys and thus eliminate, to a large extent, the prior restoring spring-tensions, correspondingly soften the "touch" at the keys, and provide an easier manual operation of returning the carriage at the end of each line.

Other features and advantages will hereinafter appear.

In the accompanying drawings, Figure 1 is a longitudinal vertical section ap-

proximately through the center of an Underwood typewriting machine, showing such parts of the type-bar action and carriage-feeding mechanism necessary to illustrate the application of the present improvement to the standard machine parts.

- Figure 2 is a full-size front elevation of the carriage-feeding unit upon a bracket detachably secured to the frame of the machine.
- 10 Figure 3 is a side elevation of Figure 2, showing the escapement-rocker-driving connections assembled in an operative relation to the carriage-feeding elements.

Figure 4 is an enlarged diagrammatic view, 15 showing the normal relation between the driving element and the controlling pallet movable with the escapement-rocker.

Figure 5 is a view similar to Figure 4, showing 20 the pallet vibrated to a position at the instant of type-impact, while one member of the pallet is about to release a tooth of the driver and another tooth of the driver is about to restore the pallet and restore the escapement-rocker.

Figures 6, 7 and 8 are diagrammatic views 25 illustrating the different positions assumed by the holding and stepping dogs in relation to two teeth of the escapement-wheel; Figure 6 shows the normal relation between the teeth of the escapement-wheel and a stepping dog; Figure 7 shows the relation of these parts at the end of 30 a down stroke of a key or at the instant of type-impact where the tooth of the escapement-wheel has passed to the control of the holding dog and the stepping dog has moved to the position 35 shown to intercept the next advancing tooth of the escapement-wheel when the rocker is restored; and Figure 8 shows the rocker restored to normal position with the stepping dog positioned between the two teeth of the escapement-wheel. The return movement of the rocker under 40 the impetus of the driver moves the stepping dog into a position to intercept the tooth 39^a of the escapement-wheel before said tooth has shifted from the Figure 7 position, due to the 45 sluggish response of the carriage-motor.

In the Underwood typewriting machine, keys 10 operate levers 11 to operate bell-cranks 12 to swing type-bars 13 about a pivot-wire 14 upwardly and rearwardly against the front face of 50 a platen 15 against the tension of a spring 16, that operates to restore type-bars upon a pad 17 and the key-levers against a pad 18. The platen 15 is mounted within a carriage having a back bar 19 formed with two lugs 20 arranged to slide 55 on a rear carriage-rail 21. The carriage is drawn in a letter-space direction by a spring-motor 22 having a tape-connection 23 to one of the lugs 20 of the carriage.

Each type-bar is provided with a heel 24 which, 60 in moving to the dotted position of Figure 1, engages a curved universal bar 25 forming part of the frame 26 pivotally mounted at the rear upon pivots 27, carried by arms 28, forming a frame that is pivotally mounted at 29 to an escapement-bracket or frame 30. The bracket 30 takes the form of an inverted U, providing two legs 31 that are secured to a base-frame 32 in the usual manner by screws 33. The escapement-bracket 30 and base 32, when assembled, form a carriage-feeding standard or unit that is removably secured to the frame of the machine by screws 34. The escapement-frame, when assembled in position, provides an upright structure to support the carriage-feeding elements, including 70 an escapement-wheel 35 and an escapement-dog- 75

rocker 36. The escapement-wheel 35 is driven in a letter-space direction by a feed-rack 36^a, movable with the carriage to engage with an escapement-pinion 37 loosely mounted to rotate about the axis of the escapement-wheel and operative to drive said wheel in a one-way direction through pawls 38 mounted upon the wheel and engaging with teeth in the pinion 37.

The tension of the spring-motor 22 tends to draw the carriage leftward in the usual manner, 80 whereby the feed-rack 36^a will rotate the pinion 37 and escapement-wheel 35 with one tooth thereof, as 39, pressing against the face of a stepping dog 40, pivotally mounted at 41 to the rocker 36 and provided with the spring 42 operative to 85 draw said dog into a stepping position against a fixed stop 43 on the bracket 30. Normally, a tooth 39 is in pressing engagement against the stepping dog 40, but when the type-bar 13 is raised to the dotted position to vibrate the universal bar 25, an ear 44, formed in the frame 26, engages a screw 45 carried by the rocker, and becomes operative to vibrate the rocker 36 to 90 move the stepping dog out of engagement with the tooth 39, said tooth passing to the control of 100 the holding dog 46 forming a part of the rocker. The escapement-mechanism may also include a check pawl 47, pivotally mounted at 48 upon the rocker and provided with a spring to normally hold the pawl in a position to prevent undue 105 backward rotation of the wheel 35, but not to interfere with the rotation of said wheel in the letter-space direction.

The escapement-rocker 36 may be formed with 110 hubs 49 at each side thereof to receive mitre-pointed pins 50 to pivotally support the rocker between the two legs 31 of the escapement-bracket. The frame 26 is provided with an ear 51 having a spring 53 connected thereto, effective to draw the frame toward a stationary pin 115 54 supported by the frame 30. From this description, it will be seen that the action of the type-bar vibrates the universal bar 25 against the tension of the spring 53, engages the screw 45 to vibrate the rocker 36, and vibrates the escapement-dogs through the field of the teeth of 120 the escapement-wheel 35 to effect a letter-spacing movement of the carriage at each type-bar movement, which is the standard Underwood construction, and further details may be had 125 in the patent to Helmond, No. 1,411,024, dated March 28, 1922.

The present invention includes an escapement-pallet 55 adjustably mounted upon one hub 49 of the rocker 36 by means of a set screw 56 130 threaded through a hub 57 of the pallet. The pallet 55 may be formed of sheet metal with the end of one arm thereof bent over at right angles to form a stop-face 58, and another arm provides a support for a stud 59 upon which a roll 135 60 is mounted to project at right angles to the plane of the pallet. To co-operate with this pallet, a star-wheel 61 operates to alternately engage the stop-face 58 and the roll 60 to provide for the escapement of one tooth of said wheel 140 at each to and fro vibration of the pallet when moved by the escapement-rocker in effecting the carriage-feeding movement.

It will be noted at Figure 4 that the stop-face 58 is concentric to the axis of the pallet 55, and one face of each tooth on the wheel 61 has a similar curvature so that the vibration of the pallet 55 from the position of Figure 4 to that of Figure 5 will provide for a smooth sliding movement of said stop-face over the stationary 150

face of the star-wheel teeth. It will also be noted at Figure 5 that the stop-face 58 is at the point of releasing a tooth 62 of the wheel 61 and that the roll 60 is in abutting engagement 5 with the face of another tooth 63, so that when the wheel 61 is rotated in any suitable manner in the direction of the arrow, the tooth 63 will become a driving element to force the roll 60 out of its path and cause a counter-vibration of the 10 pallet and restore the rocker 36 to its normal position. It will further be noted, as at Figure 4, that the stop-face 58 bottoms against the wheel 61 to determine the normal stop position for the rocker 36 under the tension of the spring 42, and 15 that the roll 60 at Figure 5 is in engagement with the tooth 63 approximately at the instant the stop-face 58 releases the tooth 62; hence said roll checks the backward throw of the dog-rocker under an impulse from the key-actuated universal 20 bar.

The star-wheel 61 is under a spring tension that operates to constantly force said wheel in the direction of the arrow, and the pallet 55 rocking in unison with the escapement-rocker 36 becomes an escaping medium for the teeth of said wheel to provide a power-driven medium for vibrating the pallet and escapement-rocker in a return direction. When the star-wheel is released at Figure 5 to the action of a wound-up 25 spring tension, the effect of said wheel upon the pallet 55 will accelerate the return movement of the escapement-rocker, and the abutting screw 45 will project the universal bar 25 to repulse the type-bar from the face of the platen more 30 quickly than the spring 53 could possibly operate.

Just how the co-operation of the pallet 55 with the star-wheel 61 affects the carriage-feeding elements is shown at Figures 6, 7 and 8. Figure 6 diagrammatically shows the normal relative positions of two teeth 39 and 39^a of the escapement-wheel with the stepping dog 40 and the holding dog 46. From this normal position of Figure 6, the dog-rocker, including the holding dog 46 and the stepping dog 40, is vibrated 40 in the direction of the arrow, which brings the several parts into the positions shown at Figure 45 7, where holding dog 46 is holding the tooth 39, and the stepping dog has moved forward against the stop 43 to intercept the advancing tooth 39^a of the escapement-wheel, the several positions 50 illustrating the relative relation of the several parts at the instant of type impact against the platen face, and when the pallet 55 has been vibrated to the position of Figure 5, where the tooth 62 is about to be released by the stop-face 58 of the pallet and the tooth 63 about to engage the roll 60 to vibrate the pallet 55 and move and shift the holding dog 46 and stepping dog 40 in the direction of the arrow *a* (Figure 7) to the 55 position of Figure 8, where the tooth 39 has been released by the holding dog 46 and the stepping dog 40 is in position to intercept the tooth 39 and be carried with the tooth against the stop-face 64, which arrests the escapement-wheel 35 at 60 the end of its letter-spacing movement.

The star-wheel 61 may be adjustably mounted on a driving shaft 65, as by a screw 66, and the shaft provided with bearings in the upper ends of two lugs 67 forming a part of the base of the escapement-support, endwise movement of said shaft being checked by a collar 68 bearing against one of said lugs. The shaft 65 extends to the side frame of the machine where the free end may be provided with a bearing in an upper right bracket 69 secured to the frame.

From this description it will be seen that the star-wheel 61 is not a constantly rotating element, but may be under a spring tension to rotate in a fixed direction, and the rotation thereof being intermittent and determined by the type-bar-actuated escapement-rocker. Such a mode of operation requires suitable means to restore the tension of the star-wheel periodically, as its power is drawn upon through the action of the pallet 55 in allowing the teeth to escape one at a time. The present invention is not concerned in any particular manner for restoring the driving power for this star-wheel. One way to accomplish this purpose, however, may be a modification of the mechanism shown and described in the patent to Henry Pitman, No. 1,417,106, dated May 23, 1922, or a train of mechanism similar to that shown in my pending application filed June 12, 1925, Serial No. 36,594, where a modification of the Pitman device is employed and which may be readily attached to the present mechanism, as by supplying the shaft 65 with a gear 70 at the free end thereof outside the casing, that is in train with an intermediate gear 71, in train with a gear 72 secured to the end of a cylinder 73 that houses a spring 74. The spring 74 operates to turn gears 72, 71 and 70 to rotate the star-wheel in a clockwise direction, and, to wind up said spring 74, the gear 72 may be in operative train with a series 100 of intermediate motion-reducing gears and pinions from a source of power which may be an electric motor, indicated as 75. A motor-driven self-winding mechanism of this nature, of course, requires checking means to prevent the cylinder from unwinding with the spring, and the starting and stopping of the motor may be automatically controlled by the spring when it reaches certain points, these control features being fully 105 set forth in said Pitman patent.

The mechanism has been described as being co-operative with a type-bar-actuated universal bar, but it is just as essential that other keys, like the space-bar, shall be operative to quickly effect a carriage-feeding movement of the carriage. To this end, the space-bar 76 is provided, in the usual manner, with levers 77 operative to rock a shaft 78, carrying an arm 79 operative to vibrate an arm 80 fixed to an extension of the frame 28. The depression of the space-bar 76 rocks the arm 80 and the frame 28 about its pivot 29 to draw the universal bar-frame 26 rearwardly until the ear 44 thereon engages the screw 45 of the escapement-rocker when the rocker is vibrated in a manner similar to that already described when actuated by the type-bar.

It will be noted at Figure 6 that the usual bevel face, indicated at 81 in dotted lines, is superseded by a flat face and that the tooth 39, in passing from the control of the stepping dog 40, will have a very slight clearance drop, which is the usual practice. It will be further noted that the interval of time between the release of the tooth 62 by the stop-face 58 and the driving engagement of the tooth 63 against the roll 60 is nil, and that the effect of the star-wheel upon the pallet 55 is practically instantaneous and provides a restoring means more effective than any bevel-dog structure to quickly effect a letter-space movement after a type-impact and to simultaneously provide a repulsing means to more quickly get the returning type-bar out of the path of an advancing type-bar, both features being conducive to greatly increase the speed 140 of manipulation of the machine.

Variations may be resorted to within the scope of the invention, and portions of the improvements may be used without others.

Having thus described my invention, I claim:—

- 5 1. In a typewriting machine and in an escapement-mechanism having a dog-rocker connected to be vibrated by the down stroke of the keys in typing, a power-driven rotary driver, and a rocker-controlled pallet having spaced-off members to co-operate with the driver, one member including a stop-face operative to release and arrest the driver, and the other member including an anti-friction roll to be displaced by the driver to forcibly restore the rocker for a letter-spacing movement. 80
- 10 2. In a typewriting machine having keys and typing elements driven thereby, a power-driven carriage and a carriage-feeding mechanism operable by the keys to letter-space the carriage, a power-driven rotary driver, and means normally operative to restrain the rotation of the driver, said means being movable by the carriage-feeding elements to become automatically effective to release the driver after each typing movement, 90 said carriage-feeding elements being then actuatable by the driver to accelerate the letter-space feed of the carriage and the return of the operated key to normal position. 95
- 15 3. Impulse return mechanism for a type bar comprising a bracket, a rocker arm pivoted in the bracket, a pallet adjustably pivoted on the rocker arm, a motor operated escapement wheel pivoted in the bracket and cooperative with the pallet to periodically give an impulse thereto and connections between the rocker arm and the type bar to impart the impulses of the pallet to the bar. 100
- 20 4. Mechanism for imparting a return impulse to a type-bar comprising a motor operated escapement wheel, a rocker arm having check and stepping pawls carried by said arm to control said escapement wheel, an oscillatable pallet coaxial and rigid with the rocker arm, a motor operated escapement wheel having teeth rotatable in a 105
- 25 5. Mechanism for giving a return impulse to a type-bar comprising a universal bar movable to give an impulse to the type-bar, a rocker arm connected to said universal bar, an oscillatable pallet having a stop prong and an impulse prong rigidly connected to the rocker arm, a motor operated escapement wheel having its axis perpendicular to the plane of movement of the pallet and also having one side of each of its teeth inclined to give an impulse to the impulse prong of the pallet, the same side of each tooth being cooperative with the stop prong of the pallet to stop and temporarily hold the escapement wheel stationary and connections between the rocker arm and the universal bar to transmit the impulse to the type-bar. 110
- 30 6. A return impulse mechanism for a type-bar comprising a toothed escapement wheel and a motor therefor, a rocker arm having escapement pawls thereon to control said wheel, the contacting faces of the pawls and teeth on the wheel being in the same plane while in contact, a pallet rigid with the rocker arm, a second escapement wheel having teeth cooperative with the pallet and a motor to operate said second escapement wheel, one of the pallet prongs being cooperative with one side of each tooth of the wheel to stop 115 and temporarily hold the wheel stationary and then release the same, and the same side of the tooth being operative on the other prong of the pallet to give an impulse to the same, and connections between the rocker arm and type bar to transmit the impulse from the impulse prong of the pallet to the type-bar. 120
